POWER LAWN MOWER

Walter B. Ford, Grosse Pointe, Mich.

Application February 23, 1955, Serial No. 34,629

Term of patent 14 years

(Cl. D40—1)

Fig. 1 is a perspective view of a power lawn mower viewed from the front and left-hand side, showing my new design;

Fig. 2 is a similar perspective view from the front and right-hand side; and

Fig. 3 is a rear elevational view thereof.

The characteristic features of my design reside in the solid line portion.

I claim:

The ornamental design for a power lawn mower, substantially as shown and described.
